UNITED STATES PATENT OFFICE

CHARLES H. OSLUND, OF WORCESTER, MASSACHUSETTS, ASSIGNOR TO THE LIQUID CARBONIC CORPORATION, OF CHICAGO, ILLINOIS, A CORPORATION OF DELAWARE

LABELING MACHINE

Application filed September 4, 1930. Serial No. 479,706.

The principal objects of this invention are to provide a labeling machine which will be capable of supplying paste to the entire rear surface of the label and will automatically lay the label in place and detach it from the pickers and then spread the label out on the surface to which it is to be applied and also to provide a form of pickers which will permit this machine to accomplish these results. 10 Other objects and advantages of the invention will appear hereinafter.

Reference is to be had to the accompanying drawings, in which

Fig. 1 is a front view of a labeling machine showing the pickers in the act of being supplied with gum;

Fig. 2 is a sectional view on the line 2—2 of Fig. 1;

Fig. 3 is a plan of the pickers with some 20 of the parts shown in the same position as in Fig. 2;

Fig. 4 is a front view showing the application of the label to the article to be labeled and the drawing away of the pickers;

25 Fig. 5 is a sectional view on the line 5—5 of Fig. 4;

Fig. 6 is a view similar to Fig. 4 showing the last position of the pickers before they move out of contact with the label, and

30 Fig. 7 is a similar view showing in full and dotted lines the operation of wiping the label down on the surface of the article to be labeled.

Ever since labeling machines have been 35 used it has usually been thought necessary to supply the label to the article with the two ends or sides gummed and with a surface at the center free from gum. There are some classes of goods which it is desired to label with pickers which have to have the gum all over the rear surface of the label. This machine is designed to provide for labeling such articles.

The invention is shown as applied to a 45 well known type of hand labeling machine and for that reason all the operating mechanism is not shown. The machine is shown, however, as provided with a label holder 10 having hooks 11 for retaining the labels, 50 these hooks projecting over the edges all

around the labels. Under this label holder, or at least adjacent to it, a pair of pickers 12 are adapted to move. In the present case, the pickers are shown as coming in horizontal position below the label box. They 55 are gummed from a gum roll 13 by the use of a transfer roll 14 which moves directly along the pickers in the manner indicated in Fig. 2. This transfer roll has a straight reciprocating motion and the means for producing that motion is not shown as it is very common in this class of machines.

The pickers 12 are mounted on arms 15 which are pivoted by two shafts 16 carried by a vertical sliding frame 17 at the top of 65 them. The adjusting stop screws 18 are shown for an obvious purpose. Springs 30 are coiled on the shafts 16 to normally hold the pickers yieldingly in the position shown in Fig. 1. The pivoted arms 15 are provided with rollers 19. The sliding frame 17 moves up and down on guides 20 by means not shown to bring the pickers from a position in which the transfer roll can move over them as shown in Fig. 1 then into a position to 70 engage the end label in the label holder 10 and finally back to a position in which the label L will be deposited on the surface of the article B to which it is to be applied. In this case this surface is shown as flat. The 75 box or other article B is carried on a stationary support.

The pickers 12 are capable of engaging the last label in the label holder because of openings 21 made through it for the reception of 85 the hooks 11 with which the label holder is supplied. On the motion of the slide 17 to its limit upward in the machine, the pickers, pressed yieldingly against this outer label and the gum already spread upon them over the entire surface of the pickers, will not only pick up the label but will apply the gum to the entire rear surface of the label.

Now as the frame 17 and parts carried thereby including the pickers 12 are brought downward, the rolls 19 on the picker arms 15 come in contact with a pair of stationary cams 22 and turn the pickers down to the position indicated in Fig. 4. They are kept in that position until the frame reaches its 100

lowermost point where the label will engage the article B as shown in Fig. 4. Then the frame moves upwardly and the pickers, without changing their angular position, will rise 5 and take the ends of the label up with them, as shown in Fig. 5, where the pickers 12 are shown just leaving the label. The label falls back.

It will be understood that the usual grip 10 finger 23 is employed, being carried on a lever or bell-crank 24 and operated by a cam or other similar means through a link 25. This grip finger comes down on the center of the label across the article B just as the label 15 comes into contact with the article. On the moving back of the pickers, this grip finger holds the label down at the center. This grip finger is the usual construction and the method of operating it has not been shown.

20 A pair of rubber wipers 26 are shown which, after the label is released from the position shown in Fig. 6, come up against the grip finger 23 and move back in opposite directions as indicated by the dotted and 25 full line positions indicated in Fig. 7. The mechanism for operating the wipers is not shown, being well known, but of course the novel features of this invention work with the old features of the labeling machine and 30 I have chosen the type of labeling machine to illustrate this invention which is provided with grip fingers 23 and wipers 26, as shown.

It will be seen that by this mechanism involving comparatively inexpensive additions 35 to the ordinary hand labeler of this type, or in fact to a machine labeler, such a machine can be converted so as to provide for gumming the entire rear surface of each label and thus equipping the machine for doing 40 work which it has not been able to do heretofore. The additions are simple and inexpensive and the operation of the machine is not altered or the number of operations changed.

45 Although I have illustrated and described only one form of the invention, I am aware of the fact that modifications can be made therein by any person skilled in the art without departing from the scope of the invention as expressed in the claims. Therefore I do not wish to be limited to all the details of construction herein shown and described, but what I do claim is:—

55 1. In a labeling machine, the combination with a label holder and a pair of pickers movable into a position to take the labels from the holder, said pickers having a combined area equal to that of a label and being pivoted on opposite sides of the frame, and extending substantially into contact with each other at the center of the machine when the pickers are arranged in a single plane, so that these two pickers will gum the entire label, 60 of means for turning the pickers backward- 65

ly away from each other as they move away from the label holder.

2. In a labeling machine, the combination with a label holder, a sliding frame and a pair of pickers carried by the sliding frame into a position to take the labels from the holder, said pickers being pivoted on opposite sides of the frame, and extending substantially into contact with each other at the center of the machine when the pickers are arranged in a single plane, of means for turning the pickers backwardly away from each other as the sliding frame moves away from the label holder. 70 75

3. In a labeling machine, the combination with a label holder and means for supporting the article to be labeled, of a sliding frame movable between the two, a pair of horizontal shafts carried by the sliding frame, a pair of pickers carried by said shafts and adapted to reach to the center of the space between the shafts, yielding means for turning the shafts to a position in which the pickers will be in the same plane, means for supplying the pickers with paste throughout their entire surfaces while they are in said position, and means for turning the pickers outwardly toward the support for the article to be labeled as the frame itself moves toward said support. 80 85 90

4. In a labeling machine, the combination with a label holder and means for supporting the article to be labeled, of a sliding frame movable between the two, a pair of horizontal shafts carried by the sliding frame, a pair of pickers carried by said shafts and adapted to reach to the center of the space between the shafts, yielding means for turning the shafts to a position in which the pickers will be horizontal, means for supplying the pickers with paste throughout their entire surfaces while they are in a horizontal position, means for turning the pickers downwardly toward the support for the article to be labeled as the frame itself moves toward said support, whereby the label gummed all over its rear surface will finally be supported by the pickers near its ends only and a grip finger adapted to come against the outer surface of the label and press the center of the label against the article on which the label is to be applied. 95 100 105 110 115

5. In a labeling machine, the combination with a sliding frame, a pair of shafts arranged in parallel position at opposite sides thereof at one end, arms yieldingly mounted on said shafts, a pair of pickers mounted on said arms, means for limiting the turning motion of said shafts to a point in which the pickers will be left in horizontal position transverse to the line of motion of the frame, in which position said pickers will come substantially into contact, stationary cams adjacent to the sliding frame, means connected with the arms and operable by the stationary cams for turning the arms and pickers there- 120 125 130

on into an inclined position downward as the frame moves downward, means for supporting the article to be labeled in a position at the bottom of the stroke of the frame, a grip finger arranged to engage the center of the label and push it against the article to be labeled when the sliding frame gets to the lowest limit of its movement, and wipers arranged and adapted to move from the grip finger outwardly along the surface of the article to be labeled to smooth the label down thereon.

6. In a labeling machine, the combination with a sliding frame, a pair of shafts carried thereby, pickers carried by said shafts and extending into a position to come substantially into contact at their adjacent edges when in the same plane, and springs for holding the pickers normally toward each other, of a pair of stationary cams and means whereby as the frame moves away from pasting position the cams will operate said shafts and turn the pickers toward the article to be labeled.

25 In testimony whereof I have hereunto affixed my signature.

CHARLES H. OSLUND.
